UNITED STATES PATENT OFFICE.

ARTHUR HUGH GOLDFINGHAM, OF NEW YORK, N. Y., ASSIGNOR TO THE
DE LA VERGNE REFRIGERATING MACHINE COMPANY, OF SAME PLACE.

EXPLOSIVE-ENGINE.

SPECIFICATION forming part of Letters Patent No. 650,583, dated May 29, 1900.

Application filed January 24, 1899. Serial No. 703,211. (No model.)

To all whom it may concern:

Be it known that I, ARTHUR HUGH GOLDFINGHAM, a subject of the Queen of Great Britain, residing in the borough of Bronx, in the 5 city and State of New York, have invented a certain new and useful Improvement in Explosive-Engines, of which the following is a specification.

The engine is adapted to employ the volatile products of petroleum as the fuel, injecting a suitable quantity of oil into air previously introduced into the cylinder. I employ two cylinders, each serving as the corresponding parts of a single engine, of the class sometimes called "four-cycle" engines, in which effective and blank revolutions are made intermittently, each blank revolution serving simply to discharge the products of combustion and admit fresh air to serve in the succeeding effective revolution. The explosions may be induced by the heat in the metal of the combustion-chamber or vaporizer, and I will describe the engine as thus operated.

The improvement relates to the provisions for introducing the oil. It may serve with other means, as electricity, for inducing the explosion without a vaporizer. I will refer to the parts generally as "cylinders." It has long been the practice to employ two four-cycle engines thus related, and to introduce the oil by two reciprocating pumps, one for each cylinder, having passages so connected as to introduce the oil in one or more fine jets, which traverse across the vaporizer or cylinder and, striking the metal on the interior of the opposite side, become vaporized and diffused in the air, forming an explosive mixture which is ignited and by its great expansion drives the engine or engines. I have discovered that it is practicable to so employ a single pump delivering oil at each revolution that a measured charge of oil will be intermittently supplied under pressure directly to the admission-port of each cylinder, but only at the 45 period of its suction-cycle, coincidentally, the admission-valve of the other cylinder being sealed against the admission of the oil under the pump-pressure by the force of the combustion-pressure within its cylinder. Also the 50 admission of the oil under the direct impulse

of the pump will result in the charge of liquid fuel being strongly jetted into the cylinder, which charge, becoming divided, will thoroughly commingle with the air therein. The two cylinders may be placed in any relations so far as direction is concerned; but I prefer for convenience and economy to have the cylinders side by side and the pistons acting upon substantially the same crank-pin or upon two coinciding crank-pins. 55

The accompanying drawings form a part of this specification and represent what I consider the best means of carrying out the invention.

Figure 1 is a vertical section presenting an 65 end view of the shaft and appurtenances. Fig. 2 is a corresponding side view. Fig. 3 is a diagrammatic view showing in vertical section certain portions on a larger scale. The view generally corresponds to Fig. 2, but showing the casings of the two valves through which the oil is delivered alternately into the respective cylinders partially turned around, so as to appear to be in the same plane. Fig. 4 is a section showing one of the valve-heads 75 and the parts immediately adjacent thereto on a larger scale. Fig. 5 is a cross-section through the longitudinally-grooved body of the valve on the line 5 5 in Fig. 4. Fig. 6 is an end view of the perforated plug through 80 which the oil is jetted. Fig. 7 represents a modification. It is a general outline corresponding to Fig. 1, but showing the two cylinders arranged in tandem one above the other.

Similar letters of reference indicate corresponding parts in all the figures where they appear.

Referring to Figs. 1 to 6, I employ an ordinary strong and rigid framework A, of cast-iron, and form integrally therewith or firmly 90 secure therein two parallel cylinders A' A² in a vertical position, each open at the lower end, over a main shaft D, which latter is provided with two coinciding cranks D' D². A piston B' in the cylinder A' and a corresponding piston B² in the cylinder A² each connects with the corresponding crank D' or D² by rods C' or C². 95

The vaporizer or combustion chamber E' above communicates with the interior of the 100

cylinder A' and is maintained at a high temperature by the rapidly-succeeding brief periods of combustion therein.

E² is a counterpart vaporizing-chamber 5 kept at a corresponding high temperature, communicating with the interior of the cylinder A².

In each vaporizer or combustion-chamber and cylinder, which I may refer to simply 10 as "each cylinder," ordinary valves worked by the engine allow the long-approved four-cycle action: First, the rise of the piston forces out through the open exhaust-valve the spent products of combustion resulting 15 from the preceding explosion; second, while receiving a jet of combustible liquid, which may be ordinary kerosene, the descent of the piston draws in through the now-opened air-induction valve K' fresh air and fills the 20 cylinder therewith, mingled with the vapor of the hydrocarbon; third, the rise of such piston with both valves closed compresses such mixture; fourth, the explosion occurs and the descent of the piston, impelled by the 25 high pressure of the exploded fluid mixture, gives an impulse to the machinery, this last being the only profitable part of the motion. The impulse received in this last stroke, being stored in the fly wheel or wheels, keeps 30 up the rotation of the engine through the succeeding three strokes—two up and one down—which form the complete cycle of operations.

The pistons B' and B² in the cylinders A' and A² descend and ascend together; but the 35 valves K' are so worked that one piston shall be performing its idle ascent and descent while the other is performing its working ascent and descent.

G is a single-acting high-pressure pump, 40 serving both cylinders A' A² by injecting kerosene or other suitable oil into each alternately. The feed of liquid fuel into the proper cylinder or evaporating-chamber and the prevention of such feed into the other at the 45 proper period is effected by timing the delivering of the pump, so that it occurs only at the period of the suction in one cylinder and coincident explosion in the other, causing the positive sealing of the admission-valve of the 50 latter against the entrance of the fuel under the direct pressure of the pump impulse. I have discovered that it is practicable to thus simplify the machinery and have successfully worked it out in practice. The oil-delivery 55 pipe H, leading from the pump G, is branched, as indicated by H' H². The two branches lead each to a corresponding vaporizing-chamber, the branch H' leading to the chamber E' and the branch H² leading to the chamber E².

60 It may be briefly stated that the respective branches contain valves I' I², each having a long guiding-bearing in the pipe or passage, and a nicely-finished conical head, which matches tightly in the hollow conical seat.

65 J' J² are helical springs, each loosely enclosing an extension or stem of the corresponding valve and abutting the one against

a fixed ring H' and the other against a corresponding ring H², secured in place in the interior of the corresponding branches and 70 each acting against a collar I' or I², respectively, fixed on the stem of its valve.

In the working of my engine the conical under face of each valve-head is held in tight contact with its conical seat by the force of 75 its proper spring J' or J² and also during all the time when it is most efficient by the strong pressure of the exploded gases, which is felt at the required period on the outer face of the valve-head. The working of the engine 80 induces by the pump G a small but reliable addition to the oil in the pipe H H' H² at a certain period in each revolution of the shaft D. The oil thus forced acts equally on both valves I' and I² in the directions to force each 85 open and deliver the oil past each into both the vaporizers E' E², connected to the upper ends of the respective cylinders A' A²; but by the conditions induced, as described, the interior of one cylinder—for example, the cylinder A'—is at that moment subjected to a 90 high pressure. Simultaneously the interior of the other cylinder A² is undergoing the suction period and is free from pressure, that cylinder being in the midst of the idle reciprocation of its piston, having just driven out 95 the spent products of combustion produced by the last explosion and is just commencing to inhale a supply of air at ordinary pressure. Thus into this cylinder the oil under 100 pressure following the path of least resistance is vigorously jetted, and as it assumes a vaporous form it is mingled with the air, forming the required explosive mixture. At 105 the next revolution of the shaft D a similar installment of oil sent up by the single pump G through the same pipe H exerts, as before, an effort to pass equally each valve I' and I², and thus to go into both vaporizing-chambers E' and E²; but it is this time refused admission to the vaporizer E² and the cylinder 110 A² by reason of the higher pressure now obtaining therein, so the opposite of the former conditions are experienced, the valve I² remaining fast on its seat, while the valve I' 115 automatically opens, and the whole installment of oil now delivered by the pump is jettisoned into the vaporizer E', and so on alternately.

Particular stress is laid on the fact that the 120 operation of the pump is so timed that the delivery of the charge of the liquid fuel only occurs at the alternate suction periods of the cylinders A' A². To permit such delivery at the period of exhaust would obviously result 125 in an appreciable loss of the high-pressure fuel through the opened exhaust-port besides entailing liability to external explosions, &c.

The combustible mixture may be exploded at the right time by various means. A hot 130 surface especially prepared for the purpose, as a hollow capsule heated by an internal or external gas-jet, or an electric spark or various other means may serve. In the particu-

lar engine shown and described the metal of the vaporizer assumes and maintains so high a temperature that aided by the heat of compression it will effect the ignition at the proper time in the cycle of operations.

The valves for the admission of air and the discharge of the spent products of combustion are distinct for the two cylinders and are operated by cams, so adjusted that the piston in each will make its effective strokes at alternate periods—that is to say, the valve K', which admits the air to the vaporizer E' and the valve (not shown) which releases the spent products of combustion from that vaporizer, and consequently from the connected cylinder A', are opened and closed through connections by the cams M' and M'/* on the same shaft M. The latter is geared to the main shaft, so as to revolve once for each two revolutions of the main shaft D. The corresponding cams (not shown) which operate the valves for the admission of air to and the discharge of the products of combustion from the other vaporizer E² are adjusted on the same shaft M, but in opposite relation thereon.

It will be understood that all the parts of the engine, as the water-jacket and the provisions for circulating water therethrough, the provisions for lubricating, &c., not here specifically described, may be of any ordinary or suitable character.

Modifications may be made without departing from the principle or sacrificing the advantages of the invention. The oil may be vaporized before passing the valves I' I², or a permanent gas may be used, simply enlarging the valves and passages and providing a pump of sufficient capacity. The distances of the valves from the respective cylinders or

the vaporizers connected therewith may be modified within wide limits. Water-jackets may be employed to maintain the valves and valve-seats at a low temperature in cases where such are judged expedient.

45

The cylinders A' A² may be placed at various distances apart, the coinciding cranks with which they connect being arranged at corresponding distances apart. The cylinders may be horizontal or at various angles 50 instead of upright. It is possible to arrange the two cylinders in tandem, both connecting in such case, of course, with a single crank. Fig. 7 shows such an arrangement. In all cases the valves K', &c., must be 55 worked so as to have the idle reciprocation of the piston in each cylinder induced at the period when the effective reciprocation is being induced in the other cylinder.

60

I claim as my invention—

The combination with two four-cycle engines arranged to make their explosive strokes alternately and having their pistons moving in unison, of a single, single-acting, fuel-pump making a delivery-stroke at each 65 revolution of the main shaft of the engine, a delivery-pipe therefor having branches leading to the cylinders and a delivery-valve in each branch as described, whereby the delivery-valve to one cylinder may yield to admit the passage of fuel while the other is held closed by the explosion-pressure in its cylinder, substantially as described.

In testimony that I claim the invention above set forth I affix my signature in presence of two witnesses.

ARTHUR HUGH GOLINGHAM.
